COMBINED TRAILER AND WIRE TENSIONER

Gerald A. M. Petersen, Santa Clara, and Robert W. Goode, Morgan Hill, Calif.; said Goode assignor to said Petersen

Filed Sept. 4, 1958, Ser. No. 52,505

Term of patent 14 years

(Cl. D14—3)

FIG. 1

FIG. 2

FIG. 3

FIG. 4

Fig. 1 is a perspective view taken from the front and to one side of a combined trailer and wire tensioner embodying our new design.

Fig. 2 is a rear elevational view of Fig. 1.

Fig. 3 is a top plan view of Fig. 1; and

Fig. 4 is a side elevational view of the same.

We claim:

The ornamental design for a combined trailer and wire tensioner, as shown.
